CLAIM

The ornamental design for a display screen with animated graphical user interface, as shown and described.

DESCRIPTION

FIG. 1 is the first image in a sequence for a display screen with an animated graphical user interface showing our new design;

FIG. 2 is the second image thereof;

FIG. 3 is a third image thereof;

FIG. 4 is a fourth image thereof;

FIG. 5 is the fifth image thereof;

FIG. 6 is the first image in a sequence for a display screen with animated graphical user interface with additional unclaimed environment; and,

FIG. 7 is an enlarged view of the display screen with an animated graphical user interface shown in FIG. 6.

The appearance of the animated graphical user interface sequentially transitions between the images shown in FIGS. 1-5. The process or period in which one image transitions to another forms no part of the claimed design. The broken lines showing the display screen forms no part of the claimed design. The broken lines showing text and portions of the graphical user interface form no part of the claimed design.

The broken line showing the enlarged view square in FIG. 6 and FIG. 7 forms no part of the claimed design.
